US00D990699S

(12) **United States Design Patent** (10) Patent No.: **US D990,699 S**
(45) Date of Patent: **** Jun. 27, 2023**

(54) **MODULE FOR THERAPEUTIC DEVICE**

(71) Applicant: **Therabody, Inc.**, Los Angeles, CA (US)

(72) Inventors: **Jaime Sanchez Solana**, Los Angeles, CA (US); **Eduardo Merino**, Los Angeles, CA (US); **Alex Zhu**, Xiamen (CN)

(73) Assignee: **Therabody, Inc.**, Los Angeles, CA (US)

(**) Term: **15 Years**

(21) Appl. No.: **29/866,589**

(22) Filed: **Sep. 19, 2022**

(51) LOC (14) Cl. **24-01**

(52) U.S. Cl.

USPC **D24/215**

(58) **Field of Classification Search**

USPC D24/133, 141, 188, 189, 190, 187, 200, D24/206, 209, 211, 212, 213, 214, 215

CPC A61H 2015/0014; A61H 19/44; A61H 2201/5025; A61H 2201/5005

(57) **CLAIM**

The ornamental design for a module for therapeutic device, as shown and described.

DESCRIPTION

FIG. 1 is a top front isometric view of a module for therapeutic device showing the claimed design;

FIG. 2 is a bottom front isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

1 Claim, 6 Drawing Sheets
